P. SUSOL,
BOTTLE STOPPER AND SEAL,
APPLICATION FILED JUNE 15, 1920.

1,355,012.

Patented Oct. 5, 1920.

FIG. 1.

UNITED STATES PATENT OFFICE.

PAUL SUSOL, OF NEWPORT NEWS, VIRGINIA, ASSIGNOR OF ONE-THIRD TO JAMES P. BRYANT, OF NEWPORT NEWS, VIRGINIA.

BOTTLE STOPPER AND SEAL.

1,355,012.

Specification of Letters Patent.

Patented Oct. 5, 1920.

Application filed June 15, 1920. Serial No. 389,158.

To all whom it may concern:

Be it known that I, PAUL SUSOL, a citizen of Czecho-Slovakia, residing at Newport News, in the county of Warwick and State 5 of Virginia, have invented certain new and useful Improvements in Bottle Stoppers and Seals, of which the following is a specification.

This invention relates to certain new and 10 useful improvements in bottle stoppers and seals and particularly to that type of bottle wherein a seal is positioned inwardly of the bottle neck and coöperates therewith to provide a stopper for the neck, the seal being 15 movable to a different position to permit the passage of the contents of the bottle through the neck and coöperating with the bottle neck to prevent the return of the seal to its closing position.

20 With the above and other objects in view, the present invention consists in the novel form, combination and arrangement of parts hereinafter more fully described and shown in the accompanying drawings, wherein like 25 reference characters indicate similar parts throughout the several views.

In the drawings,

Figure 1 is a vertical sectional view of a 30 bottle neck with a portion of the body broken away with the stopper and seal in closed positions,

Fig. 2 is a view similar to Fig. 1 with the stopper removed and the seal shifted to its open position,

35 Fig. 3 is a horizontal sectional view taken on line III—III of Fig. 1,

Fig. 4 is a horizontal sectional view taken on line IV—IV of Fig. 1,

Fig. 5 is a side elevational view of the 40 bottle neck guard removed from the neck, and

Fig. 6 is a side elevational view of the cork seal removed from the bottle neck.

Briefly described, the present invention has 45 for its main object to provide a bottle stopper that is constructed to coact with a specially formed bottle neck that is adapted when in one position, to close the outlet of the neck, and when in another position to 50 permit the contents of the bottle to flow through the neck and to be viewable to indicate the opening through the neck and prevented from returning to the neck closing 55 position. A closure cork is positioned in the outer end of the bottle neck and a guard

cap is arranged inwardly of the cork through which the controlling cord for the stopper seal passes.

Referring more in detail to the accompanying drawing, there is illustrated a bottle embodying a body 1 and a neck formed of an inner section 2 and an outer section 3 separated by an enlarged annular chamber 4 embodies an inner wall 5 and an outer wall 6, while the outer neck portion 3 is of increased cross sectional area adjacent the annular chamber 4 to provide an outer shoulder 7.

The stopper and seal associated with the bottle neck is formed of two circular cork blocks 8 adapted, when adjacently positioned as shown in Fig. 1 to completely close the inner neck section 2. The seal cork sections 8 are carried by a spring device embodying a looped portion 9 having depending legs 10 with angularly bent lower ends 11 adapted for inclosing the lower ends and inner and outer sides of the cork sections 8, the spring legs 10 having a tendency to separate to the position shown in Fig. 2, and only remaining adjacently positioned when the cork sections 8 are disposed within the bottle neck section 2.

A guard cap is permanently positioned within the neck of the bottle and embodies 85 an upper wall 12, a circular side wall 13 with radial perforations 14 therein. The cap guard is anchored within the bottle neck by the resilient arms 15 fixed at their upper ends as at 16 within the lower ends of 90 the side walls 13, while the lower ends of the resilient arms are outwardly bent as at 17 with toothed upper faces as shown in Figs. 1 and 2. In positioning the guard cap within the bottle neck, the spring arms 15 95 are moved inwardly to permit the extremities of the bent ends 17 to ride over the inner face of the bottle neck until the same extend below the upper wall 6 of the chamber 4, at which time the same will spring 100 outwardly and be permanently retained within the bottle neck. A cord 18 is attached to the looped portion 9 of the spring device and is threaded through opposite openings 14 in the guard cap, as shown in 105 Figs. 1 and 3, and suitably knotted adjacent the upper face 12 of the guard cap.

An outer sealing stopper 19 of cork or like material is positioned in the outer end of the neck section 3 to seal the entire contents 110

- of the bottle and neck. When it is desired to seal the bottle, assuming that the bottle is filled with the desired contents, the spring legs 10 are moved into adjacent positions by 5 a suitable implement and introduced through the outer end of the bottle neck until the same are received in the inner section 2 of the neck. A cord is passed through the looped portion 9 of the spring device 10 carrying the cork sections 8 and is threaded through the desired openings 14 in the guard cap. The cap has the arms 15 pressed inwardly to permit the same to ride upon the inner face of the bottle neck so that the 15 toothed ends 17 engage the outer wall 6 of the chamber 4 while the inner end of the side wall 13 of the guard cap engages the shoulder 7. The cord 18 is then knotted above the guard cap and the stopper 19 mounted in the 20 outer end of the neck. To remove the contents of the bottle, the stopper 19 is extracted and the cord 18 pulled outwardly to position the cork sections 8 in the enlarged chamber 4, at which time the spring legs 10 will separate 25 to move the cork sections outwardly and to provide a passage through the bottle neck, the contents of the bottle passing through the neck section 2, chamber 4, cap openings 14 and through the outer end of the bottle 30 neck section 3, attention being called to the fact that the diameter of the guard cap 12 is smaller than the diameter of the neck section 3 to provide a passage thereabout for the fluid. When the cork sections are positioned as shown in Fig. 2, it is impossible to 35 compress the legs 10 to return the cork sections 8 to the bottle neck section 2. While it would be possible to refill the bottle, still, the position of the cork sections 8 in the enlarged chamber 4 of the bottle neck would 40 indicate that the original contents of the bottle had been removed. While there is herein shown and described the preferred embodiment of the invention, it is nevertheless to be 45 understood that minor changes may be made therein without departing from the spirit and scope of the invention as hereinafter claimed.

What is claimed as new is:

- 50 1. A bottle seal of the type described comprising in combination with a bottle having a neck with an enlarged annular chamber in the neck and a shoulder formed upon the inner face of the neck outwardly of the 55 chamber, a bottle seal formed of cork sections, a spring device for supporting the cork sections, a guard cap within the bottle neck and engaging the outer wall of the enlarged chamber and the shoulder on the bot- 60 the neck, a cord connection between the spring device and guard cap and a closure for the outer end of the neck.

2. A bottle seal of the type described comprising in combination with a bottle having

a neck with an enlarged annular chamber in the neck and a shoulder formed upon the inner face of the neck outwardly of the chamber, a bottle seal formed of cork sections, a spring device for supporting the cork sections, a guard cap within the bottle neck and engaging the outer wall of the enlarged chamber and the shoulder on the bottle neck, a cord connection between the spring device and guard cap and a closure for the outer end of the neck, said spring device embodying resilient legs normally separated and supporting at their lower ends, the cork sections.

3. A bottle seal of the type described comprising in combination with a bottle having a neck with an enlarged annular chamber in the neck and a shoulder formed upon the inner face of the neck outwardly of the chamber, a bottle seal formed of cork sections, a spring device for supporting the cork sections, a guard cap within the bottle neck and engaging the outer wall of the enlarged chamber and the shoulder on the bottle neck, a cord connection between the spring device and guard cap, a closure for the outer end of the neck, said spring device embodying a looped section, resilient legs carried thereby and bent at their lower ends to support the cork sections.

4. A bottle seal of the type described comprising in combination with a bottle having a neck with an enlarged annular chamber in the neck and a shoulder formed upon the inner face of the neck outwardly of the chamber, a bottle seal formed of cork sections, a spring device for supporting the cork sections, a guard cap within the bottle neck and engaging the outer wall of the enlarged chamber and the shoulder on the bottle neck, a cord connection between the spring device and guard cap and a closure for the outer end of the neck, said guard cap having lateral openings therein to facilitate the passage of the connecting cord.

5. A bottle seal of the type described comprising in combination with a bottle having a neck with an enlarged annular chamber in the neck and a shoulder formed upon the inner face of the neck outwardly of the chamber, a bottle seal formed of cork sections, a spring device for supporting the cork sections, a guard cap within the bottle neck and engaging the outer wall of the enlarged chamber and the shoulder on the bottle neck, a cord connection between the spring device and guard cap and a closure for the outer end of the neck, said guard cap embodying resilient arms cooperating with the cap and the bottle neck to retain the guard cap in the bottle neck.

In testimony whereof I affix my signature,

PAUL SUSOL.
